Primary Examiner — Kevin K. Rudzinski(74) *Attorney, Agent, or Firm* — Dorsey & Whitney LLP(57) **CLAIM**

The ornamental design for a handheld spray nozzle, as shown.

DESCRIPTION

FIG. 1 is a top isometric view of a handheld spray nozzle.
FIG. 2 is a bottom isometric view thereof.
FIG. 3 is a right side elevation view thereof.
FIG. 4 is a left side elevation view thereof.
FIG. 5 is a top plan view thereof.
FIG. 6 is a bottom plan view thereof.
FIG. 7 is a front elevation view thereof; and,
FIG. 8 is a rear elevation view thereof.
